CLAIM

The ornamental design for a bendable hair rod with clasp, as shown and described.

DESCRIPTION

FIG. 1 is a perspective view of a bendable hair rod with clasp, showing our new design;

FIG. 2 is a front view of the bendable hair rod with clasp;

FIG. 3 is a rear view of the bendable hair rod with clasp;

FIG. 4 is a right side view of the bendable hair rod with clasp;

FIG. 5 is a left side view of the bendable hair rod with clasp;

FIG. 6 is a top view of the bendable hair rod with clasp;

FIG. 7 is a bottom view of the bendable hair rod with clasp; and,

FIG. 8 is a perspective view of the bendable hair rod with clasp in a bent configuration.

The broken lines shown in the drawings illustrate portions of the bendable hair rod with clasp and form no part of the claimed design.
